ABSTRACT OF THE DISCLOSURE

A device for pressing the sander belt of a belt sander machine according to the present invention comprises a pressure means in the form of a deformable bag containing fluid such as air under pressure and an overall pressure element made of a flexible material located under said pressure means, which pressure element is in contact with the sander belt. The device further comprises an intermediate means in the form of rollers positioned between said pressure means and said overall pressure element whereby excessive sanding of the leading and trailing end portions of the workpiece may be avoided.

The present invention relates to an improvement in or relating to a belt sander machine especially for wood-working, and more particularly to a device for pressing a sander belt of the belt sander machine against a workpiece.

In a device for pressing the sander belt now available, the overall pressure element is pressed downwardly by means of metallic springs so that the portion of the sander belt pressed thereby sands the surface of the wood workpiece fed into the belt sander machine. However, it is difficult for such a device to force the sander belt to contact the entire surface of a workpiece which is slightly warped or had previously been planed. Thus, the finishing by sanding or grinding of the workpiece can not be uniform with the conventional spring pressing device.

In order to overcome this fault, there is proposed a sander belt pressing device having a pressure means in the form of a deformable bag or vessel made of a flexible material and containing a fluid such as air under pressure which pressure means may press the sander belt via the overall pressure element also made of a flexible material and positioned under said pressure means against the workpiece surface. According to this proposal, however, inflation or expansion of the bag may cause the flexible overall pressure element and consequently the effective surface of the sander belt to be convex, which causes too much sanding or abrasion of the leading and trailing end portions of the workpiece.

This fault is overcome by further providing an intermediate means positioned between said air cushion and said overall pressure element, which intermediate means is rigid in the direction of sander belt movement but flexible in the direction normal thereto and preferably consists of a plurality of rods arranged side by side so that the axis of each rod is parallel to the direction of sander belt movement.

An object of the present invention is, thus, to provide an improved device for pressing a sander belt against a workpiece which device has a deformable vessel containing therein a fluid such as air under pressure supplied from any suitable source to press the sander belt via a flexible overall pressure element whereby the corresponding effective portion of the running sander belt may closely fit and contact substantially every surface portion of the workpiece to be finished, even if it is slightly warped.

Another object of the present invention is to provide

2

such a device further having an intermediate means which is rigid in the direction of movement of the sander belt but flexible in the direction normal thereto whereby excessive sanding of the leading and trailing end portions of the workpiece may be avoided.

Still further objects and advantages of this invention will be readily understood with reference to the following description and accompanying drawings, in which;

FIG. 1 illustrates a side elevation of a wide belt sander machine provided with the sander belt pressing machine of the present invention,

FIG. 2 is a front elevation of another type of machine provided with the pressing device according to the present invention,

FIG. 3 is an enlarged fragmentary section of the pressing device taken along the line III—III in FIG. 1, and

FIG. 4 is a sectional view taken along the line IV—IV in FIG. 3.

Referring now to FIG. 1 of the drawings, a preferred

embodiment of the pressing device of this invention, generally designated by *a*, is diagrammatically shown installed on a wide belt sander machine **10**. The marking **10** comprises a frame **12**, a work table **14** adapted to be vertically moved up and down by means of a reciprocator **16** such as threaded rod-gear means fixed on said frame **12**. There is also provided a control handle **18**, two guide rolls **22** and **24**, a driving roll **26**, a tension roll **28** respectively mounted rotatably on a roll support member **20** vertically standing on said frame **12**. Finally, the machine **10** includes an endless sander belt **30** of a width substantially corresponding to that of said table **14** and adapted to be driven around the rolls **22**, **24**, and **28** by means of said driving roll **26** which is rotated by a motor (not shown). The device *a* of the present invention is

shown to be fixedly mounted on the roll support member **20** for the sake of clear and simple illustration. However, it is of course possible and rather preferable to mount said device *a* removably to said roll support member **20**. The lower ends of the device project slightly with respect to the lower surface of the guide rolls **22** and **24** to press the lower horizontal run of the sander belt **30** downwardly. After setting the table **14**, which can be raised and lowered by means of the threaded rod means **16** and the handle **18**, at a level to be determined by the thickness of a workpiece *b*, said workpiece *b* is fed into the belt sander machine in the direction as shown by an arrow *c* along the table **14** by any feeding operation means (not shown). During the feeding the workpiece *b* is subjected to sand-finishing action of the sander belt **30** driven in the direction *d* and pressed downwardly by the device *a* of the present invention. The particles removed by the belt **30** are discharged through a duct **32** provided with an appropriate sucking or blowing means (not shown).

Referring next to FIG. 2, the device *a* of the present invention is mounted on a simple belt sander machine which comprises a frame **34**, a bed **38** adapted to be vertically moved up and down by means of a reciprocator means **36**, a horizontally movable table **40** with rollers **401** rotatable on rails **42** mounted on said bed **38**, a driving roll **44** and an idler roll **46** around which an endless sander belt **48** is extended to be driven by any suitable motor means (not shown). On the upper end of said frame **34** is mounted or formed a guide member **50** which slidably carries a holder member **52** for the means *a* of the present invention to enable the means *a* to be moved across the entire width of the table **40**. The workpiece fixedly supported on said table **40** may move horizontally and normal to the direction of movements of the belt **48**, the inner surface portion of which is pressed down by the device *a* positioned between the rolls **44** and **46**.

The means *a* is fixed to the holder block 52, which holder block is slidably movable along said guide means 50 in the direction normal to the direction of movement of the workpiece.

In FIGS. 3 and 4 there is illustrated in more detail the device of the present invention generally designated by *a* which may be mounted integrally or removably by any desired conventional means to the lower portion of the roll support member as designated by the numeral 20 in FIG. 1 or the holder block as represented by 52 in FIG. 2. The device *a* comprises a housing 54 having a substantially channel-like cross section (see FIG. 4) which is provided on the upper portion thereof with outwardly projecting flanges 541 and 542 to fit slidably in the roll support member or the holder block. Leg portions 543 and 544 of said channel-like housing are respectively bent inwardly at the respective free ends thereof so as to form a channel cavity in which there is disposed a deformable bag 56 made of a flexible material and expandable into a substantially rectangular shape when supplied with fluid such as air under pressure through an inlet 60 from any suitable source (not shown). Under said deformable bag 56 is positioned an intermediate means which consists of a plurality of metallic rods 58 arranged in parallel so that the axle of each said rods 58 is parallel to the direction of the sander belt movement. The cross-section of each of said rods 58 may be of any desired shape such as a square or circle. The ends of said rods 58 preferably rest respectively on the inwardly bent ends 543 and 544 of the housing legs which serves to prevent the air bag 56 from being forced out of the housing even if an excess of air is supplied thereinto through the inlet 60. Under said rods 58 there is provided a deformable member 64 made of any desired flexible material, which material defines an overall pressure element. The member 64 is mounted so that the lower portion thereof projects out of the channel cavity of the housing when the air under pressure is supplied into said air bag 56. In order to cover the open end of said cavity, a closure member 62 is provided which is preferably made of wear resistant material such as leather, glass fiber cloth, which closure member 62 contacts the inner surface of the sander belt to press it downwardly. The closure member 62 is fixed to the housing at the ends thereof in the tensile condition by any appropriate means such as bolts 70 and washers 72 as shown in FIG. 4.

Between the rods 58 and the air bag 56 and between the air bag 56 and the overall pressure element 64 there may be provided respectively flexible sheet members 66a and 66b made of sheet metal, rubber sheet, cloth or the like. The device *a* will, however, function adequately without said flexible sheet members, however.

When the pressure of the fluid such as air in the deformable bag 56 is adjusted so that the oposite ends of the

parallelly arranged rod respectively are urged against the inwardly bent leg free ends 543 and 544, the pressure element 60 presses the sander belt 68 against the workpiece. Thus, if the wood workpiece *b* on the table of the belt sander machine is warped the cover member 62 and the flexible body 64 will be deformed to displace the rods 58 such that they will conform to the shape of the workpiece and thus effect complete sanding.

From the foregoing disclosure of a preferred embodiment, the present invention will be easily understood by those skilled in the art but it should be noted that said disclosure has been given merely by way of explanation of the invention and various changes or modifications in the shape, construction and arrangement of parts as well as material thereof may be made without departing from the spirit and the scope of the claims as clearly set forth in claims hereinafter.

What is claimed is:

1. A device for pressing the sander belt of a sanding machine against a workpiece, said device comprising a housing having an open end and an abutment surface adjacent to said open end, a plurality of rods resting on said abutment surface and arranged parallel to each other and to the direction of movement of the sander belt, a deformable container in said housing and fillable with fluid under pressure to urge said rods against said abutment surface, and a flexible pressure element carried by said housing and partly projecting through the opening therein for operative engagement with the sander belt, thereby to press the sander belt against the workpiece to effect sanding thereof despite the presence of irregularities in the workpiece extending parallel to the direction of movement of the sander belt.

2. The device set forth in claim 1, wherein said housing is of channel-like construction and has a pair of legs, the outer ends of said legs being bent inwardly to define said abutment surface upon which said rods rest.

3. The device set forth in claim 1, and further comprising a flexible cover member covering said pressure element and secured to said housing, thereby to hold together said deformable container and said rods and said pressure element.
